UNITED STATES PATENT OFFICE.

ANDREW V. BAUMEISTER, OF ROCKWOOD, MICHIGAN.

KNOCKDOWN CRATE.

1,028,094.

Specification of Letters Patent.

Patented June 4, 1912.

Application filed August 29, 1910. Serial No. 579,516.

To all whom it may concern:

Be it known that I, ANDREW V. BAUMEISTER, citizen of the United States, residing at Rockwood, county of Wayne, State of Michigan, have invented a certain new and useful Improvement in Knockdown Crates, and declare the following to be a full, clear, and exact description of the same, such as will enable others skilled in the art to which it pertains to make and use the same, reference being had to the accompanying drawings, which form a part of this specification.

My invention relates to an improvement in knockdown crates, shown in the accompanying drawings and more particularly pointed out in the following specification and claims.

The object of my invention is to produce a crate simple in construction, of low cost of manufacture, and yet one in which the parts when assembled are sufficiently rigid to withstand the hard usage to which shipping cases of this character are subjected.

Another object is to provide an interlocking feature not affected by exposure or moisture,—an objection frequently raised against crates employing wooden interlocking devices.

Another feature of the invention is the means employed to lock the several parts together upon being assembled.

Another feature is the simple and novel means employed to secure the cover to the walls of the crate.

Other advantages and improvements will hereafter appear.

In the drawings accompanying this specification:—Fig. 1 is a perspective view of the crate as it would appear when in use. Fig. 2 is a fragmentary perspective view of one of the interlocking strips to which the bars forming the wall of the crate is secured. Fig. 3 is a similar perspective view of the co-acting member. Fig. 4 is a fragmentary view of the two corner members in assembled relation and locked together. Fig. 5 is a longitudinal vertical section through a portion of the crate, showing the manner of securing the cover in place. Fig. 6 is a perspective view of the crate with the cover removed, showing the manner of assembling the walls of the crate. Fig. 7 is a plan view of the crate with the cover removed disclosing the manner of se-

curing the bottom grating in position and how the latter serves to brace its side walls.

Referring now to the letters of reference placed upon the drawings:—A, A, are the side walls of the crate formed of wooden bars spaced apart and secured at their ends to the metallic strips B, B, the latter having a projecting portion extending from the ends of the bars and formed with a return bend b, in spaced relation to the body of the strip.

C, C, are the grated end walls formed of wood bars similar to the side walls and likewise secured to metallic end members D, D, formed of sheet metal having a return bend portion d adapted to interlock with the return bend of the members B secured to the side walls. The end and side walls may also be reinforced if desired with wood or other posts E to which the gratings may be secured.

B' are openings in the end members B, and D' are spring locking lugs formed in the members D by partially punching out the metal;—the lugs thus formed being bent outwardly that they may enter the openings B' of the co-acting members B, to lock the walls together. Any suitable locking device may be employed in connection with the interlocking end posts but the device shown has been found both simple and efficient.

F is a bottom grating formed of spaced wooden bars secured to the battens F', F', the latter when the bottom grating is assembled, lying adjacent to the edges of the wooden posts E, thereby securing the grating against lateral movement. The strips forming the grating are adapted to project between the two lower bars of the side walls, resting upon the lower members for support;—the two end bars being contiguous to the posts E when the bottom grating is assembled to insure against end play.

G is the top grating nailed or otherwise secured to the members H, H', H'', the construction being such that the end of the latter members abut against the end frames of the crate to provide against lateral movement.

I are plates secured to the upper bars of the end walls and projecting inwardly that they may overlap the ends of the member H' to secure the cover grating in position;—the cross bars of which rest upon the top strips of the side walls of the crate. To re-

lease the cover it is only necessary to spring the end wall sufficiently so that the fastening plate I may free the member H, when the cover may be removed.

5 In forming the cover the strips H and H² are placed contiguous to the end posts E,—the arrangement being such as to provide against lateral displacement of the cover.

10 Having indicated the several parts by reference letters, the assembling of the device will be understood. The side and end walls are joined together by interlocking the end members as indicated in Fig. 3 of the

15 drawings,—the bottom grating being placed in position before the last wall is interlocked. Upon the part D' of the members D passing the opening B' in the members B, the spring lug will enter the opening

20 thus securing the parts together. To secure the cover in place one of the end walls of the crate is sprung sufficiently to admit the end of the cross member H below the plates I;—which overlapping the end of the member H' when the parts are assembled, secures the cover in position.

Having thus described my invention, what I claim is:—

1. A knockdown crate having a bottom, 30 sides and end walls, angular corner posts secured to the ends of the side walls and provided with return bend portions, the return bend portions being provided with openings, metallic strips secured to the ends 35 of each end wall, each strip having a return bend portion interlocking with the return bend portion of an angular corner post, spring tongues carried by the return bend portions of each metallic strip for engagement with the openings in the angular corner posts, a grated cover composed of bars and battens secured together, the ends of said bars resting upon the top of the side walls when the crate is assembled, and 40 metallic locking plates secured to the end walls at the top thereof and projecting over the ends of one of the cover battens, the battens of the cover terminating short of the end walls.

50 2. In a knockdown crate, grated sides and end walls, sheet metal end posts formed in two parts, one part having a return bend

portion interlocking with a return bend portion of the other part, the return bend portion of the said other part being provided 55 with openings, and the return bend portion of one part of each end post having a spring tongue engaging in an opening in the other part of the said end post, spring locking plates secured to the tops of each end wall, 60 and a cover composed of cross bars and battens secured in spaced relation, the ends of the cross bars resting upon the tops of the side walls with the ends of the battens sprung under the metal plates of the end 65 walls.

3. In a knockdown crate, a bottom, side and end walls, locking means between the ends of the end walls and the ends of the side walls, spring plates secured to the end 70 walls and a cover composed of bars and battens secured together, the ends of the bars resting upon the top of the side walls and the ends of one of the battens sprung under the spring plates of the end walls. 75

4. In a knockdown crate, a bottom, side and end walls, locking means between the ends of the end walls and the ends of the side walls, locking plates secured to the end walls at the top thereof, and a cover resting 80 upon the side walls and sprung under the locking plates, whereby an upward pressure is exerted upon the end walls.

5. In a knockdown crate, a bottom, side and end walls, metallic strips provided with 85 openings secured to the side walls, metallic strips secured to the end walls and provided with locking tongues for engagement with the openings in the metallic strips carried by the side walls, spring plates secured to 90 the end walls at the top thereof, and a cover resting upon the side walls and sprung under the spring plates whereby a yielding and upward pressure is exerted on the end walls and the locking tongues thrown into 95 locking relation with the openings in the metallic plates carried by the side walls.

In testimony whereof, I sign this specification in the presence of two witnesses.

ANDREW V. BAUMEISTER.
